UNITED STATES PATENT OFFICE.

EUGENE EASTERLY, OF ROCHESTER, NEW YORK, ASSIGNOR TO THE SILL STOVE WORKS, OF SAME PLACE.

DESIGN FOR A WATER-FRONT FRAME.

SPECIFICATION forming part of Design No. 28,514, dated April 26, 1898.

Application filed August 23, 1897. Serial No. 649,280. Term of patent 14 years.

To all whom it may concern:

Be it known that I, EUGENE EASTERLY, a citizen of the United States, residing at Rochester, in the county of Monroe and State of New York, have invented and produced a new and original Design for a Water-Front Frame for Stoves and Ranges, of which the following is a specification, reference being had to the accompanying drawings, forming a part hereof.

Figure 1 is a perspective view of my design for a water-front frame; Fig. 2, a rear view of the same, and Fig. 3 a cross-sectional view on the line $x-x$ of Fig. 2.

Similar reference-letters in the several figures indicate similar parts.

The leading feature of my design is the water-front embodying the ends formed substantially as shown, and the concaved recesses or portions at the front and the rounded ribs at the rear.

The upper portion of the water-front (indicated by A) is substantially flat and slightly

raised at the parts A', having the steps a at the end, and the front portion is recessed, as shown, and is provided with the slightly-concaved recesses B, extending to near the end portions B', provided with the flanges B². At one end is the flange C, having the projecting portion C', and at the lower edge the flange C², a flange C³ being provided at the opposite end, as shown. At the rear of the top portion is the flange A², and the rear side of the article is provided with a series of ribs or corrugations D the reverse of the recesses B, the plain surfaces D' at the ends, and at the center the surface D². At one end on the rear side is the flange E.

I claim as my invention—

The design for a water-front frame, substantially as shown and described.

EUGENE EASTERLY.
